CLAIM

The ornamental design for a jewelry display stand,
substantially as shown.

DESCRIPTION

FIG. 1 is an enlarged perspective view of a jewelry
display stand showing my new design;

FIG. 2 is a side elevational view thereof;

FIG. 3 is a top plan view thereof, taken along line 3—3
of FIG. 2;

FIG. 4 is a rear elevational view thereof; and

FIG. 5 is a cross sectional view taken along line 5—5 of
FIG. 3.
